UNITED STATES PATENT OFFICE.

OSCAR M. LEICH, OF GENOA, ILLINOIS, ASSIGNOR TO LEICH ELECTRIC COMPANY, OF GENOA, ILLINOIS, A CORPORATION OF ILLINOIS.

SPARK-PLUG.

1,348,886.

Specification of Letters Patent. Patented Aug. 10, 1920.

Application filed March 19, 1919. Serial No. 283,566.

To all whom it may concern:

Be it known that I, OSCAR M. LEICH, a citizen of the United States, residing at Genoa, in the county of Dekalb and State of Illinois, have invented a certain new and useful Improvement in Spark-Plugs, of which the following is a full, clear, concise, and exact description, reference being had to the accompanying drawings, forming a part of this specification.

My invention relates to spark plugs of the type for use in connection with internal-combustion engines and is designed more particularly as an improvement over the spark plug disclosed in the patent issued to Albert A. Radtke, No. 1,290,780, on January 7, 1919. In the spark plug disclosed in the said patent there is shown in addition to the two spark electrodes an auxiliary co-operating electrode which is insulated and isolated from the other electrodes, but is yet in close proximity thereto, thus to increase the effect of the spark.

This present application is designed to provide an effective and simple manner of mounting the auxiliary co-operating electrode.

I will describe my invention more in detail by referring to the accompanying drawing, in which—

Figure 1 is a side-view partially in section of a spark plug constructed in accordance with my invention;

Fig. 2 is a fragmentary enlarged sectional view on line 2—2 of Fig. 1;

Fig. 3 is a sectional view on line 3—3 of Fig. 2;

Figs. 4, 5 and 6 are perspective views illustrating the auxiliary electrode and its co-operating insulating mounts;

Fig. 7 is a view similar to that of Fig. 2 of a modified form of the invention, and

Fig. 8 is a detail view illustrating more clearly the construction shown in Fig. 7.

Referring more particularly to Fig. 1, I show the customary insulating base 10 through which the central electrode 11 extends, terminating at the upper extremity in the binding post 12. The insulating base 10

is held within a metal sleeve or shell 13 through the agency of the nut 14. The metal sleeve 13 has the customary screw threaded portion 15 through the agency of which it is mounted in the engine. The metal shell

13 also carries the second main electrode 16.

As before stated, there is provided an auxiliary electrode 17, which in this instance forms part of the metal ring 18. This auxiliary electrode 17 is pointed to facilitate its sparking operations and is mounted in close proximity to the electrode 11. The auxiliary electrode 17 is entirely insulated from and isolated from the electrodes 11 and 16 and operates in accordance with the discussion of such an auxiliary electrode as set out in the said patent to Albert A. Radtke. It is of course known that the spark gap between the electrodes 11 and 16 should always be a given predetermined amount. The auxiliary electrode 17 should be closer to its co-operating electrode than the other main electrode. Difficulty is thus experienced in so mounting this auxiliary electrode that it at all times maintains the proper spark gap relationship with its co-operating main electrode.

The structure herein shown is designed particularly to aline this auxiliary electrode in such a manner that the spark gap between it and the main electrode will always be a constant predetermined amount. As well understood, this spark gap is small and for that reason accuracy in the mounting thereof is necessary. To this end the auxiliary electrode 17 is formed as part of a ring 18 of suitable metal. Two insulating blocks, respectively, the blocks 19 and 20 are provided. The block 20 has a recess 21 together with an inwardly extending slotted portion 22, the recess and slot together accommodating accurately the auxiliary electrode and its supporting ring. The auxiliary electrode is thus accurately confined in position with respect to the insulating blocks 19 and 20. The three parts 18, 19 and 20 are assembled together and then fastened into position interiorly of the shell 13; this shell being, as customary, constructed of very heavy metal and consequently not easily deformed so as to destroy the desired alinement and position of parts. After the elements 18, 19 and 20 have been forced into position, the edge of the shell 13 is swung over, as shown at 23, thus to confine these parts interiorly of said shell near the extremity thereof.

It will be readily apparent that in mounting the structure in this manner, the spark gap relationship between the parts is accurately maintained.

It furthermore makes it impossible for

the user, and at the same time unnecessary, to in any way attempt to regulate the spark gap relationship between the electrodes 11 and 17.

5. In Fig. 7, I show a modified form of the invention in which the auxiliary electrode 17^a is fixedly mounted in an insulating carrier 24, which carrier is permanently secured in position upon the shell 13^a. Even 10 though the user attempted to bend the auxiliary electrode 17^a, yet such attempted bending or adjustment will not cause any appreciable change in the spark gap because of the radial position of the said auxiliary electrode 17^a relative to the main electrode 11.

From what has been thus described, the nature of my invention will be readily clear to those skilled in the art. I claim as my invention the following:

20. 1. A spark plug of the character described having main electrodes and an auxiliary electrode, a metal sleeve carrying one of said main electrodes, a porcelain mounting for the other of said main electrodes, and insulating means carrying said auxiliary electrode fixedly carried by said metal sleeve independently of said porcelain mounting.
25. 2. A spark plug of the character described having main electrodes and an auxiliary electrode, a metal sleeve carrying one of said main electrodes, and insulating means carrying said auxiliary electrode fixedly carried by said metal sleeve, said insulating means being arranged interiorly of said sleeve and being held in position by an overhanging portion of said sleeve.

30. 3. A spark plug of the character described having main electrodes and an auxiliary electrode, a metal sleeve carrying one of said

main electrodes, and insulating means carrying said auxiliary electrode fixedly carried by said metal sleeve, said insulating means consisting of a pair of annular blocks having means to confine said auxiliary electrode between them.

4. A spark plug of the character described having main electrodes and an auxiliary electrode extending radially toward one of said main electrodes, a metal sleeve carrying one of said main electrodes; means to support the other main electrode, and insulating means carrying said auxiliary electrode fixedly carried by said metal sleeve and independent of said supporting means.

5. A spark plug of the character described having main electrodes and an auxiliary electrode extending radially toward one of said main electrodes, a metal sleeve carrying one of said main electrodes, and insulating means carrying said auxiliary electrode fixedly carried by said metal sleeve, said insulating means having means to prevent said auxiliary electrode from moving inwardly toward its coöperating main electrode.

6. A spark plug of the character described having main electrodes and an auxiliary electrode extending radially toward one of said main electrodes, a metal sleeve carrying one of said main electrodes, and insulating means carrying said auxiliary electrode, said insulating means having means to prevent said auxiliary electrode from moving inwardly toward its coöperating main electrode.

In witness whereof, I hereunto subscribe my name this 4th day of February, A. D. 1919.

OSCAR M. LEICH.
